UNITED STATES PATENT OFFICE.

RICHARD D. GALLAGHER, JR., OF NEW YORK, N. Y., ASSIGNOR TO STANDARD COUPLER COMPANY, OF NEW YORK, N. Y., A CORPORATION OF NEW JERSEY.

BUFFING MECHANISM FOR RAILWAY-CARS.

979,756.

Specification of Letters Patent. Patented Dec. 27, 1910.

Application filed September 25, 1909. Serial No. 519,552.

To all whom it may concern:

Be it known that I, RICHARD D. GALLAGHER, Jr., a citizen of the United States, residing at New York, in the county of New York and State of New York, have invented certain new and useful Improvements in Buffing Mechanism for Railway-Cars; and I do hereby declare the following to be a full, clear, and exact description of the same, 10 reference being had to the accompanying drawings, forming a part of this specification, and to the figures and letters of reference marked thereon.

This invention relates to buffing mechanism for railway cars, the objects of the invention being to secure the maximum strength without an undue increase in weight or complication, and to provide a simple structure which will dispense with 15 the necessity of building up the entire supporting framing for the working and fixed parts of the buffing mechanism and platforms.

In the accompanying drawings—Figure 1 is a plan view of a portion of one end of a car under-frame with the buffing mechanism of the present invention incorporated therein. Fig. 2 is a central section in a vertical plane of the parts shown in Fig. 1. Fig. 3 is a side elevation of the main casting from a point of view opposite to that of Fig. 2. Fig. 4 is a top plan view of the main casting. Fig. 5 is a section on the line 5—5 of Fig. 4.

Similar letters of reference in the several figures indicate the same parts.

Reference letters A and B indicate the end sill and buffer beam, respectively, and C a plurality of longitudinal sills located 40 beneath the end sill and buffer beam and forming the supports for the latter, suitable bolts, such as c being provided for connecting them together. The buffer beam is usually provided with a buffer beam extension B' and the buffer D is movably supported in front of the beam by center and side stems d, d', respectively, said stems extending back through the beam, as usual.

In accordance with the present invention, 50 the entire elastic or yielding mechanism for the buffer is carried by an integral casting which is bridged between the end sill and beam, said casting also serving as the brace or support for the center of the beam and operating to so connect the parts of the plat-

form frame that it becomes a rigid structure braced within itself against distortion from buffing strains even when such strains are sufficiently heavy to destroy other parts of the equipment. The casting referred to is 60 shown in plan in Figs. 1 and 4, the latter view showing the casting without associated parts other than the ways for the center spring barrel. The end faces e, e' of the casting are formed to abut squarely against 65 the proximate faces of the sill and beams, respectively. The body of the casting is formed with a rear, center spring housing E and a bifurcated forwardly extending portion, the arms E' of which are separated 70 sufficiently to permit of the insertion and removal of the center springs, etc. Each side of the casting is provided with a lateral extension E² having an internal chamber e² for the reception of a follower for the side 75 stem springs. The chambers e² besides having the front and rear apertures e³ for the side stem and springs have transverse openings e⁴, preferably at the top, for the insertion and removal of the followers.

The side stems d' extend back through the lateral extensions or brackets E² and have the usual keys and washers for preventing the withdrawal through the rear followers d² located in the chambers e². The side 85 springs F are confined between the rear followers d² and front followers d³ adapted to rest against the rear face of the beam. Inward movement of either side follower compresses the springs from the front end and 90 outward movement from the rear end, the rear followers, however, serve to limit the outward movement of the stems and buffer by engagement with the front walls of the chambers. It will be understood that the 95 followers are rectangular and will abut against the walls of the chambers while the spring is free to move in the cylindrical apertures e³. The center stem is held advanced by twin rear springs G located in the housing E and a front center spring H. The spring H extends into a floating spring barrel I, the rear end of which is formed for the reception of the forward ends of the springs G. At its forward end the spring 105 H bears against a center stem follower K, said center stem follower and floating barrel both being supported on ways or slides L preferably formed by angle irons bolted to the arms E' of the casting. Cover irons M 110

bolted to the top of the arms limit upward movement of the follower K and barrel I but said cover irons are readily removable to permit of the insertion and removal of the internal parts.

In the preferred construction the outward movement of the buffer is limited solely by the side stems, but inward movement is resisted by the center and side stems and 10 springs.

Having thus described my invention, what I claim as new, and desire to secure by Letters Patent of the United States, is:—

1. The combination with the longitudinal car sills, end sill and buffer beam supported thereon and the buffer movable toward and from the buffer beam, of a buffer controlling mechanism embodying an integral casting lying above the longitudinal sills with its 15 outer and inner ends against the buffer beam and end sill, respectively, said casting having laterally extending integral brackets on opposite sides intermediate the ends and 20 having chambers therein, side stem followers in said chambers, side stem springs supported by said brackets, and center stem springs 25 located centrally within the casting.

2. In a buffing mechanism for railway cars, the combination with the end sill, buffer beam and buffer movable toward and from 30 the beam, of a casting interposed between and abutting the end sill and beam, said casting having a center housing for the center stem spring, lateral projections forming 35 housings for the ends of the side stem springs, and transverse openings in the last mentioned housings for the admission of the side stem spring followers.

3. In buffing mechanism for railway cars, 40 an integral casting having its rear face formed to abut centrally against the car end

sill, a bifurcated forwardly extending portion formed to abut the buffer beam and to receive the rear end of the center stem, center stem spring guides and supports within 45 said casting, lateral extensions on the casting each forming a side stem spring follower housing and transverse openings in said housings for the admission and removal of the followers.

4. In buffering mechanism for railway cars, an integral casting forming housings for the center and side stem springs and a support for the buffer beam, said casting having a central chamber for the end center stem springs, forwardly extending arms on each side of the center and between which the center springs are located, transversely extending brackets each formed with a chamber for the reception of a side stem spring 50 follower and apertured for the passage of the side stem, and each chamber having a transverse opening for the admission and removal of the follower.

5. In a buffering mechanism for railway cars, the combination with the end sill and buffer beam, of an integral casting abutting the proximate faces of the sill and beam, said casting being formed with an inner 65 housing for center springs, forwardly extending arms between which the center stem and forward springs work, laterally extending brackets having chambers for side stem 70 spring followers, guides projecting from the proximate faces of the forwardly extending arms, a center spring barrel held by said 75 guides, and center and side springs and stems.
